UNITED STATES PATENT OFFICE

162,739

TOWEL HOLDER

Edgar Lambert, Detroit, Mich.

Application July 14, 1950, Serial No. 11,169

Term of patent 14 years

(Cl. D33—16)

To all whom it may concern:

Be it known that I, Edgar Lambert, a citizen of the United States and a resident of the city of Detroit, county of Wayne, State of Michigan, have invented a new, original, and ornamental Design for a Towel Holder, of which the following is a specification, reference being had to the accompanying drawing, forming a part hereof:

Fig. 1 is a perspective view of a towel holder showing my new design;

Fig. 2 is a side elevational view of the same;

Fig. 3 is a top plan view of said towel holder

Fig. 4 is a front elevational view of the same.

I claim:

The ornamental design for a towel holder as shown.

EDGAR LAMBERT.
